UNITED STATES PATENT OFFICE

141,862

DESIGN FOR A PICTURE FRAME OR THE LIKE

George Evans, Chicago, Ill.

Application March 22, 1945, Serial No. 118,626

Term of patent 7 years

(Cl. D29—20)

To all whom it may concern:

Be it known that I, George Evans, a citizen of the United States, residing in Chicago, in the county of Cook and State of Illinois, have invented a new, original, and ornamental Design for a Picture Frame or the Like, of which the following is a specification, reference being had to the accompanying drawing, forming part thereof.

In the drawing

Fig. 1 is a front detail view of the upper left hand corner of a picture frame embodying my new design;

Fig. 2 is a rear detail view of the upper right hand corner of the same;

Fig. 3 is a side elevational detail view of the upper left hand corner of the same; and

Fig. 4 is a front elevational view, on reduced scale, of a picture frame showing my new design, it being understood that the ornamental details shown in Figs. 1, 2, and 3 are repeated in the complete frame.

I claim:

The ornamental design for a picture frame or the like, as shown and described.

GEORGE EVANS.
